SCREW PENCIL

Karl Valdemar Jørgensen, Hellerup, Denmark

Application February 4, 1935, Serial No. 4,853
In Denmark February 16, 1934

7 Claims. (Cl. 120—18)

The invention relates to screw pencils of the kind having a rotary feeder mechanism for advancing leads forward through a hollow point of said pencil.

- 5 The invention has for its object to provide a pencil of this kind in which fresh leads can be introduced into the hollow point without opening the magazine for spare leads, but simply by turning the feeder mechanism backwards.
- 10 A further object of the present invention is to provide means, whereby this procedure can be repeated many times as long as spare leads remain in the magazine.

A still further object of the invention is to 15 provide means for attaining these advantages in such a manner that the leads, in filling up the magazine, have not to be placed in any distinct order, but can be filled in side by side as usually in such pencils, using a magazine for spare leads.

20 According to the invention the aforesaid advantages are obtained without making the use of the pencil more difficult than the use of an ordinary screw-pencil, and without making it necessary for the user to make other adjustments 25 or movements with the pencil-parts than ordinary.

Further the invention comprises no frail parts, but can be carried out using simple and rigid parts, so that the pencil in accordance with the 30 invention will have a great strength, will be durable in use, and will not be easy to bring out of proper function.

According to the invention, the said advantages are attained by using a spiral guide face 35 in the magazine leading from the wall of the magazine to the axis of the pencil, and a slide co-operating with the said guide face, one of the said parts being firmly attached to the casing of the pencil, while the other one is connected to 40 the feeder mechanism by means of a friction coupling or the like.

On the drawing is shown by way of exemplification but not of limitation, two pencils according to the invention.

45 Fig. 1 showing a longitudinal section of one construction.

Fig. 2 is a substantially longitudinal sectional view on an enlarged scale of the upper portion of the pencil.

50 Fig. 3 is a top plan view of the pencil with the cap removed.

Fig. 4 is an enlarged sectional view of the rotary cap.

Fig. 5 is a sectional view of the slit pipe taken 55 on lines 5—5 of Figure 4.

Fig. 6 is a longitudinal sectional view of the coupling and associated parts.

Fig. 7 is a substantially transverse sectional view of the barrel and magazine taken on lines 7—7 of Figure 1, and

Fig. 8 the bottom end of another construction 5 of the pencil, in longitudinal section.

The pencil consists of a hollow case 1, on to which a point 2 is screwed, the said point being fitted with a central channel 3, in which the lead can be advanced by a feeder mechanism. Close 10 behind the point 2 there is provided a cavity serving as a magazine 4 for spare leads.

Into the top end of the pencil a guide 5 is 15 screwed, which is shown to a larger scale in Figs. 2 and 3. The guide is shaped mainly like a hollow bushing, which by means of a flange 6 can be screwed firmly against the end of the pencil, a pencil clip 7 being inserted between the 20 said parts in a manner known per se.

On the side of the guide 5 that faces inward, a stop 8 is provided, which is shaped as a stopping lug.

In the guide 5 a sleeve 9 is loosely inserted, 25 which at the end projecting into the pencil is fitted with a stopping lug 10 adapted, in a manner further described below, to cooperate with the stopping lug 8 on the guide 5. In the sleeve 9 a threaded pipe 11 is attached, which 30 may for instance be produced by winding a metal strip, in such a manner that a helical channel 12 is formed.

35 Into the threaded pipe a slit pipe 13 is inserted, which is shown to a larger scale in Figs. 4—6. The slit pipe 13 has a longitudinal channel 14, and terminates inside of the pencil in an outward flange 15. To the top end of the slit pipe 13 a cap 16 is attached, by means of which the pipe can be rotated from the outside. In the slit pipe 13 a feeder rod 17 is inserted, 40 which is fitted with a tooth 18 extending through the slit 14 and projecting into the channel 12 of the threaded pipe 11.

45 Resting against the flange 15 there is provided, on the slit pipe 13, an outer tubular coupling part 19, which by means of its bottom 20 rests against the flange 15. In the coupling part 19 a compression spring 21 is inserted, one end of which presses against the bottom 20, whereas the other end presses against an outward flange 22 on an internal tubular coupling part 23, which by means of an inward flange 24 supports the inner end of the threaded pipe 11, in such a manner that the outer coupling part, with 50 a force dependent on the pressure of the spring 55

21 and the friction between the parts is coupled loosely to the threaded pipe 11 as well as to the slit pipe 13.

In the construction shown in Figs. 1-7, a guide face 25 is attached to the magazine 4, which guide face is shaped as a part cylindrical and part spiral wall, the inner winding of which has the same radius as the leads used, and is concentric with the axis of the pencil. To the outer coupling part 19 a slide 26 is attached, which in the construction shown is fitted with a pin 27 engaging a corresponding hole in the bottom 20 of the outer coupling part 19, and supports a wing 28, which freely can be swung about the axis of its pivot pin 27. The slide is disposed eccentrically in relation to the axis of the pencil.

In the construction shown in Fig. 8, the slide 26 has its pin 27 inserted in a hole provided in the pencil point 2 eccentrically in relation to the axis of the pencil, and the guide face 25 is firmly attached to the outer coupling part 19.

Supposing a lead to be contained in the channel 3, and the feeder rod 17 to rest against the inner end of this lead, and the magazine 4 to be filled with leads 29 (in Fig. 2 two loose leads are shown) it will be possible, by rotating the cap 16 to the right, to turn the slit pipe 13, and thereby, the feeder rod 17, and consequently the tooth 18, which engages the helical channel 30 12 in the threaded pipe 11, will be pushed forward, and thereby the lead will gradually be pressed out through the channel 3.

When in this manner the lead has been pushed all the way out, at the same time as it has been consumed entirely, the procedure according to the invention is as follows:

The cap 16 is turned to the left. Hereby the friction caused by the coupling 19-24 between the slit pipe 13 and the threaded pipe 11 will cause the latter to be rotated to the left together with the sleeve 9. This condition, however, will only last until the stop 10 strikes the stop 8. Then the threaded pipe 11 will remain stationary, and by a further rotation to the left of the slit pipe 13 the feeder rod 17 will be moved clear up to the top of the pencil, the tooth 18 finally clicking over the extreme end of the threaded pipe 11. As soon as the feeder rod is heard to click, the same is known to be screwed entirely home. After this the cap 16 should again be turned to the right. In the same manner as before, and caused by the friction-coupling 19-24, the threaded pipe 11 will at the start be turned to the right together with the slit pipe 13. Hereby the slide 26 will also be turned to the right, and will thereby slide along the guide face 25. Hereby the said slide will strike the leads 29 contained in the magazine 4, and the wing 28 will press the outermost lead 50 into the innermost winding of the guide face. After this, the slide 26 cannot move any further. By the continued rotation of the cap 16, the friction in the coupling 19-24 will therefore be overcome, and the threaded pipe 11 will therefore stand still, after which the feeder rod 17 will be moved forward and will strike the inner end of the lead held in the inner winding of the guide face 25, and will push the lead directly into the channel 3 in the point, whereupon a fresh lead has been introduced in the pencil.

This action can be repeated, as long as any leads are left in the magazine 4.

The modified construction shown in Fig. 8 operates in the same manner. Only the relative motion of the slide 26 and the guide face 25 is

here effected in a different manner in that the guide face 25 is connected, by means of the coupling 19-24, to the feeder mechanism, while the slide 26 is stationary in the pencil.

The present invention is distinguished by its great simplicity and ease of operation, and by the feature that no special care is required from the user of the pencil, especially because the leads do not have to be deposited in the magazine in any definite order. Notwithstanding the great advantage attained by the automatic filling of the pencil, no other motions have to be made than in the case of an ordinary screw pencil, in which the inserting of a new lead affords that one single lead has to be shaken out of the opened magazine, and a fresh lead has to be inserted into the channel 3 by hand. Also for such a pencil the feeder rod 17 has in fact to be screwed back, which is the only motion required by the present device.

The construction may be modified in respect to certain details. Thus especially the coupling mechanism may be constructed in other manners than the one shown and described, and similarly the feeder mechanism, which does not form any part of the invention proper, may be of some other kind than the one shown here by way of example. It is only necessary that the feeder mechanism used can cause the feeding forward of the lead by a rotation about the axis of the pencil. The slide 26 and the guide face 25 may also be produced in other manners, the essential feature being merely that the guide face should have a central winding in which the leads, by a motion at right angles to their longitudinal axis, can be introduced, and thereby can be caused to stand co-axially to the axis of the pencil. It should be noted especially that the guide face may be made in one with the casing of the pencil, or may form a special part of the coupling member 19.

I claim:

1. In a screw pencil comprising a tubular casing with a rotary pushing mechanism in the rear portion thereof and the forward portion thereof forming a magazine for spare leads, two co-operating parts to guide the leads comprising a member having a spiral guide face leading from the wall of said magazine to the axis of the pencil, a slide adapted to move relatively along said guide face, a friction connection coupling for attaching one of said two co-operating parts to the rotary part of said pushing mechanism.

2. In a screw pencil comprising a tubular casing with a rotary pushing mechanism in the rear portion thereof and the forward portion thereof forming a magazine for spare leads, two co-operating parts to guide the leads comprising a member having a spiral guide face leading from the wall of said magazine to the axis of the pencil, a slide adapted to move relatively along said guide face, a friction connection coupling for attaching one of said two co-operating parts to the rotary part of said pushing mechanism in such a manner that the pushing mechanism will be adapted to rotate freely, if the resistance against the relative movement of the said guide face in relation to the said slide is great.

3. In a screw pencil comprising a tubular casing with a rotary pushing mechanism in the rear portion thereof and the forward portion thereof forming a magazine for spare leads, two relatively co-operating members for bringing the leads into the axis of the pencil, consisting of, a member having a spiral guide face leading from the

wall of said magazine to the axis of the pencil, and a slide adapted to move relatively along said guide face, a friction coupling attaching one of said relatively cooperating members to the rotary part of said pushing mechanism, the other member being attached to the casing of the pencil.

4. In a screw pencil with a tubular casing carrying in its rear portion a rotary pushing mechanism comprising a slit pipe with a push-bar inserted in a threaded pipe and its forward portion forming a magazine for spare leads, two relatively co-operating members for bringing the spare leads one after another into the axis of the pencil and consisting in a member having a spiral guide face leading from the outer wall of said magazine to the axis of the pencil and a slide adapted to move along said guide face, one of said relatively cooperating members being connected to the rotary pushing mechanism by means of a frictional coupling consisting of an outer cylindrical coupling part resting against an outer flange of said slit pipe, a helical spring placed in said outer coupling part pressing against an outer flange on an inner coupling part resting with an inner flange against the end of said threaded pipe, the other of said relatively co-operating members being connected to the casing of the pencil.

5. In a screw pencil, a (1) tubular pencil casing carrying in its rear portion a rotary pushing mechanism comprising a slit pipe with a push-bar inserted in a rotary threaded pipe and its forward portion forming a magazine for spare leads, said pencil casing having a fixed stop and said threaded pipe bearing a stop to engage said fixed stop, thereby preventing the threaded pipe from being rotated more than one revolution in relation to the pencil casing, (2) two cooperating parts to guide the leads comprising a member having a spiral guide face leading from the wall 40 of said magazine to the axis of the pencil and

a slide adapted to move relatively along said guide face, and a (3) frictional connection coupling attaching one of said two relatively cooperating parts with the rotary part of said pushing mechanism.

6. In a screw pencil with a tubular casing carrying in its rear portion a rotary pushing mechanism, a magazine for spare leads, two cooperating parts to guide the leads comprising a member having a spiral guide face leading from the wall 10 of said magazine to the axis of the pencil, an eccentrically disposed slide, adapted to move relatively along said guide face, a friction connection coupling for attaching one of said two relatively co-operating parts to the rotary part of said 15 pushing mechanism.

7. In a screw pencil with a tubular casing with a rotary pushing mechanism in the rear portion thereof and the forward portion thereof forming a magazine for spare leads, comprising a threaded pipe, a flanged slit pipe with a push-bar inserted in said threaded pipe, two relatively co-operating members for bringing the leads into the axis of the pencil consisting in a member having a spiral guide face leading from the outer wall of the said magazine to the axis of the pencil and a slide adapted to move along said relatively co-operating members to the rotary pushing mechanism, said frictional coupling, comprising an outer cylindrical coupling part resting against the flange of said slit pipe, a helical spring placed in said outer coupling part pressing at one end against the lower end thereof, and an inner coupling part having an outer flange at its upper end to receive the upper end of the spring and an inner flange at its lower end against which the end of said threaded pipe rests, the other of said 20 relatively cooperating members being connected to the casing of the pencil.

KARL VALDEMAR JORGENSEN. 40
